DESIGN FOR A LIPSTICK HOLDER OR THE LIKE

Emile Norman, El Monte, Calif., assignor to Lucien Lelong, Inc., Chicago, Ill., a corporation
of Illinois

Application January 29, 1945, Serial No. 117,647

Term of patent 14 years

(Cl. D86—10)

To all whom it may concern:

Be it known that I, Emile Norman, a citizen of the United States and a resident of the city of El Monte, in the county of Los Angeles and State of California, have invented a new, original, and ornamental Design for a Lipstick Holder or the like, of which the following is a specification, reference being had to the accompanying drawing forming a part thereof.

On the drawing:

Figure 1 is a perspective view of a lipstick holder or the like showing my new design; and Figure 2 is a cross-sectional view taken through the handle end of the holder on substantially line II—II of Figure 1 showing the configuration of the plastic ornamentation on the end of the holder.

I claim:

The ornamental design for a lipstick holder or the like, as shown.
